COVER FOR SMOKING PIPES

Albert Weinstock, Brooklyn, N. Y.

Application July 21, 1949, Serial No. 105,997

3 Claims. (Cl. 206—41)

1

This invention relates to new and useful improvements in covers for smoking pipes, and, more particularly, the aim is to provide a novel and valuable such cover (for instance, of a kind especially adapted to be made of leather sheet material or some other suitable preferably generally limp and flexible material), and a cover characterized by the fact that within the same there may be housed the entirety of a pipe, stem as well as bowl, with, at the same time, the pipe able to be quickly and snugly encased in the cover substantially in a glove-fit manner; yet a cover which, nevertheless, may be substantially instantaneously opened, whenever it is desired to free the pipe for smoking, by easy and expeditious slip-off of the cover from the pipe, following a snapping free of the releasable securing instrumentality for a single opening through which the entirety of the pipe is entered into and removed from the cover.

A further feature of the invention is that, for the throttling of noxious odors from the pipe, the new cover, after insertion of the entirety of the pipe therein, with the pipe then occupying the entire interior of the cover, the latter being always entirely closed adjacent to the suction orifice at the free end of the bitt of the stem, is further suitably closable opposite the top of the bowl cavity of the pipe, and this last solely by the use of a single closure means as aforesaid. Due to the aforesaid glove-fit, the covered pipe occupies substantially no more room in the pocket of the smoker than the pipe when uncovered. Further, due to the general limply flexible nature of the cover, the latter, after removal of the pipe, will take up so little room in the pocket of the smoker that its temporary storage there is a matter of no inconvenience or otherwise of any consequence.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a perspective view of the pipe cover constructed in accordance with the present invention.

Fig. 2 is a longitudinal vertical sectional view of Fig. 1.

Fig. 3 is a partial horizontal sectional view taken on the line 3—3 of Fig. 2.

2

Fig. 3-A is a similar view to Fig. 3 showing a modification thereof.

Fig. 4 is a perspective view of the pipe cover constructed in accordance with a modification of the present invention.

Fig. 5 is a horizontal sectional view taken on the line 5—5 of Fig. 4.

Referring now to the drawings more in detail, and first to the modification shown in Figs. 1 to 3, the new cover as a whole is designated 10. It will be noted that said cover is in and of itself a self-complete entity; and that, on the one hand, it is for housing completely the entirety of a pipe, and, on the other hand, it is not a part merely of a major casing having storage spaces therein for other articles than the pipe.

The cutting and seaming together of the various sections of sheet material employed for fabricating the cover may be pursuant to judgment 20 and convenience, in any way; as the concept of the invention is broader than such design details. The manner of establishing such seams, if and where present, may be any desired; for example, stitching, where the sheet material is 25 leather or the like, or a heat-sealing procedure where a heat-softenable plastic is the sheet material. Also, a hard plastic, such, for instance, as Bakelite, may be used at one end of the cover, and as so used fittable in the main part of the 30 cover.

The cover 10 is comprised of two main subdivisions, one a stem stall 11, entirely closed at its outer end; and the other, a bowl stall 12. As shown in Fig. 1, said stall 12 is in part comprised 35 of a floor-like end portion of the bottom longitudinal wall of the stem stall 11, said floor-like end portion, at or rather just beyond the inner end of the stem stall 11, projecting beyond the longitudinal roof wall of the said stem stall; and in part comprised of a wall 14 curved to 40 U-extension in top plan and with the convex side of the U-shaped wall 14 directed toward the outer end of the stem stall 11.

Also incorporated in the cover 10 is a closing flap 15. This flap may be a separate piece, but, as here shown, is indicated as an integral continuation of said floor-like end portion of the bottom longitudinal wall of the stem stall 11; said continuation being in a direction opposite to that 45 of the direction of extension of the stem stall 11 away from the bowl stall 12.

Also shown as included in the cover 10 is a pair of complementary snap fastener elements 16 and 17; one fixed on the bowl stall 12, at the 50 exterior thereof and at the location illustrated,

and the other fixed on the flap 15 near the free end thereof. The placements of these elements, and the shaping and dimensions of the flap 15, are all such, as will be noted, that, after insertion of a pipe free end of its stem foremost into the cover 10, the flap 15 may be given two transverse folds so as finally to become disposed as shown in dot and dash lines, in Fig. 2, and then with the fastener elements 16 and 17 in perfect mating relationship.

In Fig. 3-A the wall 14^a of the cover 10^a is shown to be completely circular and may be held together by a snap fastener 14^b or the like.

The modification of the pipe cover shown in Figs. 4 and 5, is similar to that shown in Figs. 1 to 3, except for the provision of means for stiffening the top portion of the U-shaped wall 14' and for gripping the bowl of the inserted pipe.

The stiffening and gripping means is characterized by a C-shaped member 18 formed of flexible metal and extended about the inside of the U-shaped wall 14' adjacent the top thereof. At spaced points, the U-shaped wall 14' is formed with spaced pairs of slots 19 through which the C-shaped member 18 is extended for mounting the C-shaped member 18 in position. As shown in Fig. 5, the ends 18^a of the C-shaped member are bent slightly outward away from each other for guiding the bowl of the pipe into position within the C-shaped member 18.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. In a cover for a smoking pipe, a pair of superimposed elongated sections having their edges secured together providing a stall for the stem of a pipe, the lower of said sections being longer to have a portion extended beyond the upper of said sections, a U-shaped wall section secured along its bottom edges to the side edges of said extended portion and to the adjacent end of the upper of said elongated sections forming a stall for the bowl of the pipe, and a flexible C-shaped member extended along the inner face of said U-shaped wall section closely adjacent the top edges thereof for stiffening the top portion of said U-shaped wall to grip the bowl of the pipe and retain it in position within said bowl stall.

2. In a cover for a smoking pipe, a pair of superimposed elongated sections having their

edges secured together providing a stall for the stem of a pipe, the lower of said sections being longer to have a portion extended beyond the upper of said sections, a U-shaped wall section secured along its bottom edges to the side edges of said extended portions and to the adjacent end of the upper of said elongated sections forming a stall for the bowl of the pipe, and a flexible C-shaped member extended along the inner face of said U-shaped wall section closely adjacent the top edges thereof for stiffening the top portion of said U-shaped wall to grip the bowl of the pipe and retain it in position within said bowl stall, said U-shaped wall having spaced sets of vertically extended slots through which said C-shaped member is laced mounting the same in position on said U-shaped wall.

3. In a cover for a smoking pipe, a pair of superimposed elongated sections having their edges secured together providing a stall for the stem of a pipe, the lower of said sections being longer to have a portion extended beyond the upper of said sections, a U-shaped wall section secured along its bottom edges to the side edges of said extended portion and to the adjacent end of the upper of said elongated sections forming a stall for the bowl of the pipe, and a flexible C-shaped member extended along the inner face of said U-shaped wall section closely adjacent the top edges thereof for stiffening the top portion of said U-shaped wall to grip the bowl of the pipe and retain it in position within said bowl stall, said U-shaped wall having spaced sets of vertically extended slots through which said C-shaped member is laced mounting the same in position on said U-shaped wall, said C-shaped member having the ends of its side arms turned slightly away from one another for guiding the pipe bowl into position within said C-shaped member.
